UNITED STATES PATENT OFFICE.

FREDERICK L. NITSCH, OF SYRACUSE, NEW YORK, ASSIGNOR, BY MESNE ASSIGNMENTS, TO GEORGE F. SAX, OF SYRACUSE, NEW YORK.

MACHINE FOR SHAPING CANDLE ENDS.

1,380,582.

Specification of Letters Patent. Patented June 7, 1921.

Application filed June 9, 1919. Serial No. 302,683.

To all whom it may concern:

Be it known that I, FREDERICK L. NITSCH, a citizen of the United States, and a resident of Syracuse, in the county of Onondaga and State of New York, have invented a certain new and useful Machine for Shaping Candle Ends, of which the following is a specification.

This invention has for its object a machine for shaping the ends as the butt ends of candles, which is particularly simple and compact in construction and highly efficient, rapid and durable in use, and it consists in the novel features and in the combinations and constructions hereinafter set forth and claimed.

In describing this invention, reference is had to the accompanying drawings in which like characters designate corresponding parts in all the views.

Figure 1 is a side elevation, partly in section, of one embodiment of my machine.

Fig. 2 is a horizontal sectional view taken on approximately the plane of line 2—2, Fig. 1.

Fig. 3 is an end elevation, partly in section, looking to the right in Fig. 2.

Fig. 4 is an enlarged sectional view taken on the plane of line 4—4, Fig. 2.

Fig. 5 is a cross-sectional view taken on line 5—5, Fig. 4, one of the dies and plungers being omitted.

Fig. 6 is a detail view showing in elevation the carriage for the movable jaws of the candle holding means.

Fig. 7 is an elevation of the butt end of the candle.

This machine for shaping candle ends comprises generally, means for engaging and holding the shank of the candle with one end as the butt end projecting, shaping means movable into engagement with the projecting end to compress and shape the same.

The candle holding means comprises a segmental fixed jaw 1 mounted in a horizontal position on the bed 2 rising from the base, a carriage 3 and segmental jaws or die sections carried by the carriage, the carriage being movable at an angle toward and from the face of the jaw 1 to carry the jaws thereon toward and from the die or jaw 1.

As here shown, the carriage 3 is provided with a fixed jaw 4 and a yielding or spring pressed jaw 5 normally extending in advance of the jaw 4 and hence when the candle is laid on the jaw 1 and the carriage 3 moved vertically, the yielding jaw 5 first engages and holds the candle and further movement of the carriage 3 compresses the springs 6 of the jaw 5 until the fixed jaw 4 engages the candle.

The carriage 3 moves in suitable upright ways 7 carried by a bracket 8 extending upwardly from the base 9 of the machine.

As here shown, the machine is adapted to operate on two candles at the same time and the jaw or die 1 is double and likewise each of the jaws 4, 5 are double.

The fixed jaws 4 are here shown as pivotally mounted between their die cavities in order to have an equalizing action as the jaws engage the candles and said jaws 4 as here illustrated are suspended by means of a link 10 having rounding ends 11, 12, the end 11 being located in a suitable bearing in the jaw 4 between the die cavities thereof and the end 12 being located in a suitable bearing in a plate 14 secured to the carriage 3 in any suitable manner as by cap screws 15, the cap screws extending through vertical slots 16 in the plate 14 in order to permit a vertical adjustment of the jaw 4 for different sizes of candles. This vertical adjustment is determined by set screws 17 threading through suitable lugs 18 on the carriage and abutting against the upper edge of the plate 14.

The end shaping means is movable with a reciprocating carriage 19 having flanges 19^a at its sides which move in ways formed in the frame 20 mounted on the base 9, and said means comprises tubular dies 21 supported by the carriage in axial alignment with the candle holding die sections 1, abutments or plungers 22 movable axially of the tubular dies 21.

This shaping means also includes a tubular closure 23 encircling the die 21 and normally projecting in advance of the same toward the opposing end of the candle holding means, this tubular closure being slidably mounted in a guide 24 in the advance end of the carriage 19 and being pressed outwardly by springs 25 arranged in suit-

able passages 26 in the front end of the carriage in which passages also move tubular stems 27 provided at opposite ends of a head 28 connecting the tubular closures, the 5 springs 25 being interposed between the bottoms of the passages and the bottoms of passages in the tubular stems as seen in Fig. 1.

The tubular dies 21 are mounted on heads 29 arranged in the guide 24 for the tubular 10 closures and are secured to the heads 21^a of the tubular dies 21 in any suitable manner as by screws 29^a.

The plungers 22 are mounted in these heads 29 and remain stationary. The carriage 19 carries the die and closures toward 15 the candle holding means until the closure abuts against the candle holding means whereupon the carriage 19 continuing to move, moves the dies 21, axially of the tubular closures 23 and at the same time the plungers 22 are moved axially into the dies 21 to compress the projecting end 30 of the candle 31 and shape the same into the form 20 shown in Fig. 7.

25 The means for actuating the movable parts of the machine comprises a main drive shaft 32 journaled in suitable bearings 33, 34 mounted on the base and power transmitting mechanism between this drive shaft 30 and the movable parts.

The power transmitting means between 35 the drive shaft 32 and the carriage to reciprocate the same in its guide 3^a comprises rock arms 35 and 36 mounted on a shaft 37 journaled in a suitable bearing carried by a 40 bracket 38, a cam 38 mounted on the shaft 32 and coacting with a follower 39 at the end of the arm 35, and a link 40 pivoted at 41 to the arm 36 and at 42 to the carriage 45 3, this link being here shown as adjustable endwisely by means of a turnbuckle 43.

The cam 38 is a scroll cam and in order 45 to hold the roller 39 engaged therewith a counterweight 44 is provided on an arm 45 also mounted on the shaft 37 and arranged on the opposite side of the shaft 37 from that on which the arm 36 is located.

The connection between the shaft 32 and the carriage 19 for the end forming dies 21 50 and closure 25 comprises a link or pitman 46 pivoted at 47 to the carriage and mounted at its other end on a crank pin 47 here shown as provided on one side of the cam 38. The link 48 is also provided with a suitable turnbuckle 46^a for adjusting the link thereof.

60 The plungers or abutments 22 are actuated relatively to the carriage and the dies 21 by means of suitable pushers 49 mounted on the carriage 19 and coacting with sliding rods 50 which thread into the rear ends of the plungers 22. The rods 50 slide in passages provided in a standard 51 rising from the frame and extending through an open-

ing in the carriage 19, this carriage being 65 in the general form of a rectangle when viewed in top plan, see Fig. 2, the dies 21 being supported on the front side of the rectangle, the pushers 49 on the rear side of the rectangle. 70

The starting positions of the rods 50 and hence the plungers are determined by adjustable stops 52 threading on the front ends of the rods and abutting against the upright standard 51, these stops being held 75 in position by set screws 53.

In order to prevent the rods 50 and the plungers 22 from movement rearwardly during rearward movement of the carriage 19, friction brake means is provided consisting of a spring pressed shoe 55 arranged in a vertical passage in the standard 51 and pressing against the flattened sides of the rods 50, the springs being inserted between the shoes 55 and blocks 56 80 threading into the passages in the upright 51 in which the shoes 55 are located.

Owing to the shoes 55 the abutments or plungers 22 are held from retrograde movement during the rearward movement of the 90 carriage 19 and the dies 21 so that the abutments act as strippers and reduce the strain on the candle during the rearward movement of the dies.

The means for controlling the operation 95 of the shaft 32 comprises a clutch section 57, Fig. 2 slidably mounted on the shaft 32 and movable into and out of engagement with the complementary clutch section 58 on a drive wheel 59 on the shaft, and means for 100 operating the clutch section 57. This operating means consists of a rock shaft 60 journaled in suitable bearings 61 on the base 9 and having a handle 62 at the front end of the machine for shifting the clutch 105 section 57 into engagement with the section 58, and mechanism for automatically shifting the section 57 out of engagement with the section 58 at the end of each cycle of movement. 110

The shaft 60 operates a suitable yoke or fork 63 coacting with the clutch section 57. The mechanism for automatically shifting the clutch section out of engagement with the clutch section 58 comprises a lever 64 mounted on a shaft 60 on which the yoke 63 is mounted, see Fig. 3, and a cam point or pin 65 mounted on the periphery of a wheel 66 which is mounted on the outer end of the shaft 32. 115

As the shaft 32 completes its rotation the pin 65 engages the outer end 67 of the lever 64 and depresses the same and the downward movement of the lever is transferred to the shaft 60 which rocks the yoke 63 and carries the clutch section 58 out of engagement with the clutch section 57. 125

The dies 21 are locked from movement

5 relatively to the carriage 19 by means here shown in Fig. 5 as a wedge 69 extending into a passage located in the carriage 19 in the top thereof between the dies 21 or the heads 21^a, the wedge being held in position by a screw 70 threading in said passage against the top of the wedge. The wedge is provided with means for pushing it out of the passage, this means consisting of a spring 10 pressed pusher or pin 71, Fig. 5, extending axially of the wedge beyond the end of the same and striking the bottom of the passage in which the wedge is located, the pin being yieldingly pressed in position by a spring 72 in order that it may yield while the wedge is being tightened by the plug 70, a plug 15 73 threading in the wedge against the top of the spring 72.

20 In use, the dies 21 may be of any suitable shape and as here shown they are formed with conical cavities formed with flutes in order to form a conical butt on the candle and in operation, the candles are placed on the dies and pushed inwardly 25 against the ends of the abutments or pushers 22 moving the pushers rearwardly to the limit of their movement against the resistance of the spring pressed shoe 55.

25 The handle 62 is then moved to the right (that is downwardly, Fig. 2, to shift the clutch 57 into engagement with the clutch section 58) whereupon the shaft 32 is rotated, first causing the cam 38 to move the carriage 3 downwardly to carry the dies 5 30 and 4 successively into engagement with the shanks of the candles on the dies 1.

35 During this movement the crank pin 57 is moving in the upright rear arc of its orbit so that the carriage 19 for the die sections has very little forward movement. However, as soon as the candle is clamped by the die sections 4 and 5, the crank pin is moving 40 in the lower portion of its orbit causing the carriage 19 to move forwardly, first carrying the closure 23 into the position shown in Fig. 4 where it abuts against the end of the candle holding dies 1 and 5 then moving the dies 21 into the closures; compressing the butt end of the candle and shaping it. The 45 closure prevents the escape of any of the material during the compression of the butt.

50 However, clearance passages 75 may be provided in the heads 29 for any excess of material. As the crank pin moves rearwardly in the upper part of its orbit the carriage 19 is moved to its starting position and as the shaft 32 completes its rotation, the pin 65 on the wheels 66 engages the lever 64 and shifts the clutch 57 to the left, Fig. 3 55 out of operative position.

60 During the last half of the rotation of the shaft, the carriage 19 is carried to its starting position but the plungers 22 are held from retrograde movement by the spring

65 pressed shoes 55 and facilitate the stripping of the dies 21 from the formed candle ends.

What I claim is:

1. A machine for shaping candle ends comprising means for holding the shank of the candle with one end projecting, tubular 70 die, an abutment forming the bottom of the die, a carriage for the die and the abutment, and means for actuating the carriage to carry the die and the abutment as a unit toward the candle holding means to shape 75 the candle end and for moving the carriage away from the candle holding means to remove the die from the candle and means for holding the abutment from retrograde movement during the retrograde movement of 80 the carriage and the die, substantially as and for the purpose described.

2. A machine for shaping candle ends comprising candle holding means with one end projecting; an axially movable closure 85 arranged in alinement with the candle holding means, a tubular die movable axially in the closure, said closure normally projecting in advance of the die toward the axial holding means, and means for successively 90 moving the closure and the die as a unit toward the candle holding means and moving the die in the closure toward the holding means, substantially as and for the purpose set forth. 95

3. A machine for shaping candle ends comprising candle holding means, a carriage, a tubular closure carried by the carriage and movable therewith axially relatively to the candle holding means, a die supported 100 by the carriage and movable relatively thereto, the die being movable in a closure, means for actuating the carriage, and means for actuating the die relatively to the carriage, substantially as and for the purpose de- 105 scribed.

4. A machine for shaping candle ends comprising candle holding means, and means for holding the candle with one end projecting, a reciprocally movable carriage 110 formed with a guide opposed to the candle holding means, a tubular closure in the guide arranged in alinement with the candle holding means, the closure being movable lengthwise of the guide, a die extending 115 into the closure and movable axially therein and having a portion movable in the guide relatively to the carriage, means for reciprocating the carriage, and means for actuating the guide, substantially as and for the 120 purpose specified.

5. A machine for shaping candle ends comprising means for holding the shank of the candle with one end projecting, and shaping means movable toward and from 125 the candle, the holding means comprising a jaw, a carriage movable toward and from the face of the jaw, and a yielding jaw car-

- ried by the carriage, and means for actuating the carriage and the shaping means, substantially as and for the purpose described.
5. 6. A machine for shaping candle ends comprising means for holding the shank of the candle with one end projecting, shaping means movable toward and from the candle, the holding means comprising a jaw, a carriage movable toward and from the face of the jaw, a jaw fixed to the carriage and movable therewith, a yielding jaw supported by the carriage and projecting in advance of the fixed jaw on the carriage, and means 10 for actuating the carriage and the shaping means, substantially as and for the purpose specified.
15. 7. A machine for shaping candle ends comprising means for holding the shank of the candle with one end projecting and movable shaping means, the holding means comprising a bed and clamping means movable toward and from the bed in a direction at an angle to the face of the bed, and means 20 for actuating the clamping and shaping means successively, substantially as and for the purpose specified.
25. 8. A machine for shaping candle ends comprising means for holding the shank of the candle with one end projecting, a tubular die arranged in alinement with the candle holding means, an abutment movable axially in the die and means for moving the die onto the end of the candle and the abutment in one direction as a unit against the end of the candle, and for shifting the die in a retrograde direction, and means for holding the abutment from retrograde movement during retrograde movement of the die, substantially as and for the purpose set forth.
30. 9. A machine for shaping candle ends comprising means for holding the shank of the candle with one end projecting, a carriage, a tubular die arranged in alinement with the candle holding means, an abutment arranged in alinement with the die and movable relatively thereto, a carriage for the die, means for actuating the carriage, the carriage having means for engaging the abutment and moving the same into the die during the movement of the die onto the candle end, and means for holding the abutment from retrograde movement with the carriage, substantially as and for the purpose specified.
35. 10. A machine for shaping candle ends comprising means for holding the shank of the candle with one end projecting, a tubular closure, a tubular die movable in the closure, the closure projecting in advance of the die and the closure and the die being movable axially toward and from the candle holding means, an abutment movable axially 40 of the die, and means for actuating the closure, the die and the abutment, substantially as and for the purpose specified.
45. 11. A machine for shaping candle ends comprising means for holding the shank of the candle with one end projecting, a tubular closure, a tubular die movable in the closure, the closure projecting in advance of the die, and movable into engagement with the candle holding means and the die being 50 movable in the closure when the closure engages the holding means, and means for actuating the closure and the die substantially as and for the purpose set forth.
55. 12. A machine for shaping candle ends comprising means for holding the shank of the candle with one end projecting, a tubular closure, a tubular die movable in the closure, the closure projecting in advance of the die, and movable therewith and movable into engagement with the candle holding means and the die being 60 movable in the closure when the closure engages the holding means, an abutment plunger movable axially of the die, and means for actuating the closure and the die and for actuating the plunger after the die moves axially in the closure, substantially as and for the purpose described.
65. 13. A machine for shaping candle ends comprising candle holding means, a carriage formed with a guide arranged coaxially with the candle holding means, a closure 70 slidable in the guide, and movable by the carriage into engagement with the holding means, a die mounted on the carriage 75 and slidable in the closure, the closure projecting in advance of the die, a spring normally holding the closure in advance of the die, a plunger slidable axially of the die, and means for successively actuating the carriage and the plunger, substantially as and for the purpose specified.
75. 14. A machine for shaping candle ends comprising means for holding the shank of the candle with one end projecting, a die supported by the carriage and movable therewith, the die being arranged in advance of the candle holding means, a plunger supported by the carriage and movable therewith axially of the die, a fixed support, a power transmitting part carried by the fixed support and coacting with the plunger, and the pusher associated with the carriage and movable into engagement with the power transmitting part after the carriage has carried the die a predetermined distance, substantially as and for the purpose set forth.
80. 15. A machine for shaping candle ends comprising a base, means for holding the shank of the candle mounted on the base, and comprising a jaw mounted on the base, and a jaw movable toward and from the first jaw, a carriage on which the second

mentioned jaw is mounted, a second carriage movable on the base and shaping means supported by the second carriage and movable coaxially toward and from the candle holding means, a drive shaft carried by the base, power transmitting parts between the drive shaft and the first carriage, and between the drive shaft and the second carriage, and means mounted on the base for controlling

the actuation of the power transmitting means by the shaft, substantially as and for the purpose specified.

In testimony whereof, I have hereunto signed my name, at Syracuse, in the county of Onondaga, and State of New York, this 15 22nd day of May, 1919.

FREDERICK L. NITSCH.
